Application December 20, 1937, Serial No. 180,895

10 Claims. (Cl. 179—1)

This invention relates to microphone apparatus and more particularly to a microphone employing stiffness-controlled transducers and having uni-directional characteristics.

In many acoustical applications it is useful to have a microphone which is sensitive to sound waves incident upon it from one direction, and which is notably less sensitive to sound waves incident upon it from other directions. Such a result may be obtained by providing a pair of electro-acoustic transducers, one of which is actuated by the difference in pressure between two points along the path of a sound wave, and the other of which is actuated by the pressure at a point in the path of the sound wave. For convenience, the first type of transducer referred to, will be called the pressure-difference operated electro-acoustic transducer, and the last mentioned type will be called the pressure operated electro-acoustic transducer.

An object of this invention is to provide an improved microphone, which employs a combination of transducers having different directional characteristics to obtain an overall uni-directional result. A specific object is to make the combination of a stiffness controlled pressure-difference operated transducer and a stiffness-controlled pressure-operated transducer available in a microphone suitable for use with standard amplifying equipment. Any of the well-known stiffness-controlled transducer movements can be used in conjunction with my invention, condenser, carbon, or piezo-electric crystal types being cited as examples.

Another object is to provide simple means by which such a pair of transducers may be connected in proper relation so that their output currents will be in proper correspondence to provide the desired overall directional characteristics.

Still another object is to provide a uni-directional microphone comprising a pair of transducers of different directional characteristics, in which the correspondence of output currents is achieved by the use of passive networks. The expression "passive networks" as used in this specification denotes electrical networks composed of combinations of elements such as resistances, inductances, and capacitances.

In stiffness-controlled transducers, the voltage generated due to the sound wave is essentially proportional to, and in phase with, the total net pressure developed by the sound waves. In the specific case of transducers employing Rochelle salt crystal elements, the voltage generated for a

given pressure is quite independent of the ambient temperature throughout the usual range of room temperatures. The internal impedance of the crystal itself, however, changes in a ratio of the order of 3 to 1 throughout the same temperature range. One of the important objects of my invention is to provide a network in conjunction with Rochelle salt crystal transducers of different directivities to achieve correspondence of voltages for proper uni-directional action at all important sound-frequencies, and throughout the usual range of room temperatures.

Since a uni-directional microphone is composed in general of two transducers, one of which presents essentially non-directional characteristics at all important frequencies, and the other one of which presents essentially bi-directional characteristics at all important frequencies, it is often advantageous to be able to use one of the transducers at a time to permit a choice of directional characteristics. Still another object of my invention is the use of transducers of impedance such that a suitable switching device can be inserted into the electrical circuit including the related electrical network without introducing difficulties inherent to switching at very high or very low impedances. Another object is to arrange a multi-directional transducer, in which the directivity can be controlled by a simple switching device housed in the microphone case. Other objects of my invention will become apparent as the specification proceeds.

An embodiment of the invention is illustrated in the accompanying drawing, in which—

Figure 1 is a schematic view showing the transducers in cross section and indicating the electric circuit; Fig. 2, a diagrammatical view showing the equivalent electric circuit; Fig. 3, a view illustrating the directional characteristics of the pressure-difference operated transducer, the view being taken with reference to a substantially horizontal plane; Fig. 4, a view illustrating the directional characteristic of the combined pressure-difference operated transducer and pressure-operated transducer when the apparatus is adjusted for uni-directional characteristics as described elsewhere in this specification; and Fig. 5, a circuit showing a modified embodiment of the invention.

As shown in Figure 1, A designates a pressure-difference operated transducer; B, a pressure-operated transducer; and N, an electrical network which corrects the frequency response of the transducer A so as to be suitable for combination with the output of the transducer B

in order to obtain the desired directional characteristics.

The pressure-difference operated transducer A is disposed in upright position and has a pair of diaphragms 10 and 10^a facing front and back directions respectively. Each of these diaphragms is mechanically connected to the piezo-electric crystal 11 so as to actuate the crystal upon movement of the diaphragms by the sound waves. A pair of conductors 12 and 12^a are connected with crystal 11 and receive the voltage generated by the transducer. It is apparent that the voltage generated by transducer A, hereinafter known as E₁, is proportional to the difference in the sound pressures on each of the two diaphragms. Being proportional to the pressure-difference between two points in space, this voltage is seriously affected by a change in the frequency of the sound wave, though the pressure of the sound wave remains constant.

The pressure-operated transducer B is shown immediately below the transducer A with the diaphragm 13 in a position substantially horizontal. However, the position of the pressure-operated transducer B relative to the pressure-gradient element A may be altered if so desired, and displacement from the above described position will serve the purpose of bringing together or apart the acoustic centers of symmetry of the transducers, and thus alter the combined directional characteristics of the two. Such displacement is to be regarded as within the limits of this invention.

The diaphragm 13 is connected mechanically with the piezo-electric crystal 14, and conductors 15 and 15^a, connected with the crystal, are adapted to receive the voltage E₂ generated by this transducer. The complete microphone assembly, including the transducers, the electrical network elements and the desired switching device, is preferably included within a suitable housing 22 shown in dotted line. It is evident that the electrical network elements and switching device may be placed within a separate envelope if desired.

Each of transducers A and B have capacitive internal impedance, and in the equivalent electrical circuit shown in Fig. 2 the transducer A is represented by the alternator 16 which generates voltage E₁ together with its equivalent internal capacitance C₁; and the transducer B is represented by the alternator 17, which generates voltage E₂, together with its internal capacitance C₂.

The cable D' by which the electrical impulses are delivered to the receiving equipment may be of any suitable construction. For reasons which appear more clearly hereinafter, this cable should preferably have a predominant shunt capacitance of between 100 to 2000 micro-micro-farads. If desired, this conducting line or cable may comprise a wire 18 which is insulated from and encased in a sheath 19 which is grounded and forms the other side of the line. The shunt capacitance of this conducting line is represented in the equivalent circuit of Fig. 2 by the capacitance C₃. In the absence of sufficient parallel capacity of the conducting line, a condenser of suitable value may be inserted.

In connecting the cable with the transducers, I prefer to use a three-way switch 20 which may be of any suitable type. The three positions of this switch are designated in Fig. 1 as 1, 2 and 3. It may be stated here that for uni-directional operation the switch is in position 1, and Figs.

2 and 4 are indicative of circuit conditions and directivity characteristic, respectively, when the switch is in this position.

With switch 20 in position 1, the pressure-difference transducer A is connected to the conducting line D' through a parallel combination of a resistor R which may have an impedance value between 0.5 and 10 megohms and a condenser C with a capacitance value between 10 and 100 micro-micro farads, and which with the capacitance C₃ comprises the electrical network N by which the voltage developed at transducer A is made to represent the intensity of the sound energy received, according to principles set forth in my copending application Serial No. 172,840, on Microphone apparatus, filed November 4, 1937. Preferably, the impedance of R should be equivalent to the total series capacitance of the circuit including transducer A at a frequency in the lower part of the audio-frequency range, such as, say, 100 cycles per second, and the capacitive reactance of C made equal numerically to the resistance of R at a frequency subsequently referred to as the "critical frequency," at which half the wave length of sound equals the effective acoustical front-to-back distance of transducer A. This distance may be taken as the shortest front-to-back path around the supporting frame, from the center of one diaphragm to the other, or, if one of the diaphragms were eliminated, from the center of the single remaining diaphragm on one side, around the frame to the center of said diaphragm on the other side. In the transducer shown as A this front-to-back distance, subsequently called "d", is approximately three inches, thus providing a critical frequency of 2200 cycles per second. As explained in my copending application previously referred to, at frequencies above the critical frequency the transducer A operates substantially as a simple pressure device because of the "obstacle effect" which obtains because of its size, and the distance d can be made to be any amount depending upon available space, and other considerations therein discussed, say, for example, between one and five inches.

Also, at this position of switch 20, the pressure-operated transducer B is connected to conducting line D' through a condenser C₄ which is preferably of the adjustable type and which may have a value of between 40 and 500 micro-micro farads. With this arrangement, it is seen that two parallel branches are formed in the circuit, one branch including the pressure-difference operated transducer A and the parallel combination of resistance R and condenser C, and the other branch including the pressure-operated transducer B and the condenser C₄, and that each of these branches is connected to the conducting line having the shunt capacitance C₃.

If switch 20 is turned to position 2, it is seen that the pressure-operated transducer will be disconnected from the circuit and only the pressure-difference transducer will be connected to the conducting line. If switch 20 is turned to position 3, the pressure-difference transducer will be disconnected from the circuit and the pressure-operated transducer B alone connected to the line, the variable condenser C₄ being also excluded from the circuit. It should be noted that it is not necessary to exclude condenser C₄ in order to use the pressure-operated transducer alone, but it is advantageous to do so in order to obtain the maximum voltage at the receiving apparatus.

Operation of the device when switch 20 is on point 3 is equivalent to the operation of single pressure-operated piezo-electric microphone as commonly used and known. As thus operated, the microphone is substantially equally sensitive to sounds from all directions in the horizontal plane.

With switch 20 on point 2, the microphone is sensitive to sound waves approaching from both front and rear. It will be observed that the directional sensitivity varies as the cosine of the angle of incidence, and the directivity characteristics may be indicated as shown in Fig. 3. Due to the presence of the comparatively large resistance R, the effective voltage across the shunt capacitance C₃ is rendered substantially independent of sound frequency at most frequencies in the audio range. A more elaborate demonstration of this fact will be found in my copending application Serial No. 172,840 for Microphone apparatus, filed November 4, 1937.

When switch 20 is in position 1, the outputs of the two transducers will be combined and the effective voltage E_r will be the vector sum of the voltages due to each of the transducers. The purpose of the adjustable condenser C₄ is to enable the outputs of the two transducers to be balanced so as to secure the desired directional characteristics.

By applying well known electrical laws, it may be shown that the effective voltage E_r, when switch 20 is on point 1, may be given very nearly by the equation:

$$35 \quad E_r = \frac{E_2 R C_p + k P a \frac{d}{v} \cos \theta}{R(C_p + C_3)} \quad (1)$$

where

P is the root-mean-square pressure of the sound wave,

40 a is the effective area of one of the diaphragms of A,

d is the length of the acoustic path between diaphragms 10 and 10^a,

45 k is a constant relating the total force upon crystal to voltage developed,

v is the velocity of sound,

E₂ is the root-mean-square voltage developed in the pressure-operated element,

50 R is the value of the series resistance,

C_p is the equivalent series capacity of the pressure element, constituted by a series combination of C₂ and C₄,

C₃ is the shunt capacitance of the conducting line, and

55 θ is the angle of incidence of the sound wave upon the pressure gradient element.

When the sound waves approach the microphone directly from the front, θ is zero, and cos θ is unity, hence the effects of the potentials due to the pressure and pressure-difference units are additive. If θ is 180°, then cos θ is -1, and the effects of the two potentials are subtractive. I prefer to make the value of C_p such that the two terms of the numerator of Equation I will be equal and opposite in sign when θ is 180° (corresponding with a sound wave approach toward the rear diaphragm 10^a).

70 Thus, the overall effective voltage developed or the combined response will be substantially zero to sound waves approaching directly from the rear of the microphone. For this condition the directional characteristics of the microphone will be represented by the curve described by the

equation $p = (1 + \cos \theta)$, which, as shown in Fig. 4, is the well known cardioid curve.

Referring again to the Equation I it is seen that C_p is a series combination consisting of relatively large crystal capacity C₂ and a relatively small capacity C₄. Hence a change in C₂, as might be produced by temperature change, would have practically no effect upon the magnitude of C_p, and such a change would only slightly affect the directivity characteristics.

It is understood that means other than condenser C_p may be employed for obtaining correspondence between the outputs of the two transducers for overall uni-directional characteristics. For example, as is seen by Equation I, the value of R may be adjusted for such operation. However, since the frequency response characteristic of transducer A, at least throughout a part of the audio spectrum, depends on the value of R, and also because of mechanical considerations, I prefer to adjust the system by a change of the series capacitance in the pressure-operated transducer branch of the circuit. By using a variable condenser in this branch of the circuit, the system may easily be adjusted for the desired directional characteristics without altering the desired action of the electrical network N.

It is apparent that by adjusting the value of the added condenser C₄, the relative importance of the pressure-operated element may be changed, and the overall directional characteristics accordingly altered.

By operating switch 20, the directivity characteristics of the microphone may be made either non-directional, by-directional, or uni-directional, as may be desired for any particular use or application.

The above description is not intended to restrict the invention to the specific circuits shown diagrammatically in Fig. 1, and its electrical equivalent shown in Fig. 2, since it is evident that the outputs of the transducers can also be combined in what may be termed a series arrangement. Thus Fig. 5 shows an alternative equivalent circuit in which the voltage developed across condenser C₃' due to bi-directional transducer 16 is added to the voltage drop across condenser C₃'' due to non-directional transducer 17 by a series arrangement of the condensers. Condenser C₄ is as before used to adjust the voltage developed by the non-directional transducer across its condenser C₃''. In this particular modification, I have found that the voltage adjusting condenser C₄, along with C₃'', may be dispensed with entirely, leaving generator 17 in series with the effective output of transducer 16 as developed across condenser C₃', and the output leads of the microphone, provided generator 17 is designed to produce the exact voltage required for the desired directional characteristics. However, in this particular modification, I prefer to use the arrangement shown in equivalent in Fig. 5 because of practical considerations.

I have described only two embodiments of the invention and it is apparent that many changes may be made in the apparatus as described without departing from the spirit of the invention. The values of the circuit constants given in this explanation are not to be regarded as exclusive or as constituting limits of the invention.

The foregoing detailed description has been given for clearness of understanding only and no unnecessary limitations should be understood therefrom, but the appended claims should be

construed as broadly as permissible, in view of the prior art.

I claim:

1. In a microphone, a pressure-difference operated piezo-electric transducer; an electrical circuit including the pressure-difference operated piezo-electric transducer and microphone output conductors presenting a shunt capacitance of 200 to 2,000 micro-micro farads, and a resistor having a resistance value between 0.5 and 10 megohms connected in series with and between the above-mentioned transducer and the microphone output conductors; a pressure-operated piezo-electric transducer connected in series relationship with a variably adjustable condenser of 20 to 200 micro-micro farads capacitance, which series arrangement of transducer and condenser is connected across the microphone output conductors.
2. In a microphone, a piezo-electric transducer operating by difference of pressure at two regions in a sound wave, the effective acoustical distance between said regions being substantially greater than one-half the wave length of the highest frequency to be received; a circuit between the above-mentioned transducer and the receiving apparatus, which circuit includes a conducting cable presenting shunt capacitance, and a parallel combination of a resistor and a condenser connected in series between the above-mentioned transducer and the conducting cable, the resistor having a resistance value numerically equal to the capacitive reactance of the cable at a relatively low frequency in the audio range, and the condenser having a reactance equal to the resistance value of the resistor at a frequency for which the effective acoustical distance between the two regions in the sound wave is substantially equal to one-half the wave length; a piezo-electric transducer operated by the pressure of the sound wave at a region in the vicinity of the above-mentioned two regions; an electrical circuit for interconnecting the transducers and the conducting cable; and adjusting means for providing equal output voltages from both transducers at the conducting cable for sound incident from a given direction.
3. In apparatus of the character set forth in claim 2, adjusting means consisting of a variably adjustable condenser in series relationship with one of the transducers, for providing equal output voltage from the transducers at the conducting cable.
4. Apparatus of the character set forth in claim 2, in which the values of the circuit elements are as follows: equivalent parallel capacitance of the conducting cable, 200 to 2,000 micro-micro farads; resistance value of the resistor in the parallel branch, 0.5 to 5 megohms; capacitance of the condenser in parallel with the above-mentioned resistor, 20 to 200 micro-micro farads; distance between the pressure-sensitive regions of the pressure-difference transducer, 1 to 5 inches.
5. In a microphone, a pressure operated transducer having substantially uniform frequency response, a transducer operating by difference of pressure at two regions in a sound wave, the effective acoustical distance between said regions being substantially greater than one-half the wave length of the highest frequency to be received, said second-mentioned transducer having a rising frequency response up to a critical frequency within the audio range and a substantially

constant frequency response above said critical frequency in circuit combination with a network inserting a loss proportional to frequency below the critical frequency and independent of frequency above the critical, and circuit means for interconnecting the transducers so that the voltage output at the terminals of the device for sound incident from a given direction is substantially less than for sound waves approaching from the opposite direction, throughout a substantial range of audio frequencies.

6. In a piezo-electric transducer operated by difference of pressure at two regions in a sound wave; an electrical circuit including the pressure-difference operated piezo-electric transducer and microphone output conductors presenting a shunt capacitance of more than 200 micro-micro farads, and a resistor having a resistance value between 0.5 and 10 megohms connected in series with and between the above-mentioned transducer and the microphone output conductors; a pressure-operated piezo-electric transducer connected in series relationship with a condenser of 20 to 200 micro-micro farads capacitance, which series arrangement of transducer and condenser is connected across the microphone output conductors.

7. Apparatus of the character set forth in claim 2, in which the values of the circuit elements are as follows: equivalent parallel capacitance of the conducting cable, more than 200 micro-micro farads; resistance value of the resistor in the parallel branch, 0.5 to 5 megohms; capacitance of the condenser in parallel with the above-mentioned resistor, 20 to 200 micro-micro farads; distance between the pressure-sensitive regions of the pressure-difference transducer, 1 to 5 inches.

8. In apparatus substantially as described in claim 2, there being an effective acoustical distance between said regions of 1 to 5 inches.

9. In apparatus substantially as described in claim 1, switching means adapted to combine the transducers so that either the unidirectional, bi-directional or nondirectional characteristic can be selected.

10. In a microphone, a transducer operating by difference of pressure at two regions in a sound wave, the effective acoustical distance between said regions being substantially greater than one-half the wave length of the highest frequency to be received; a circuit between the above-mentioned transducer and the receiving apparatus, which circuit includes a conducting cable presenting shunt capacitance, and a parallel combination of a resistor and a condenser connected in series between the above-mentioned transducer and the conducting cable, the resistor having a resistance value numerically equal to the capacitive reactance of the cable at a relatively low frequency in the audio range, and the condenser having a reactance equal to the resistance value of the resistor at a frequency for which the effective acoustical distance between the two regions in the sound wave is substantially equal to one-half wave length; a transducer operated by the pressure of the sound wave at a region in the vicinity of the above-mentioned two regions; and an electrical circuit for interconnecting the transducers and the conducting cable, both transducers providing equal output voltages at the conducting cable for sound incident from a given direction.

CERTIFICATE OF CORRECTION.

Patent No. 2,184,247.

December 19, 1939.

BENJAMIN BAUMZWEIGER.

It is hereby certified that error appears in the printed specification of the above numbered patent requiring correction as follows: Page 4, second column, line 12, claim 6, after "In a" insert microphone, a; and that the said Letters Patent should be read with this correction therein that the same may conform to the record of the case in the Patent Office.

Signed and sealed this 30th day of January, A. D. 1940.

(Seal)

Henry Van Arsdale,
Acting Commissioner of Patents.
